CLAIM

We claim the ornamental design for a beacon light, as shown and described.

DESCRIPTION

FIG. 1 is a perspective view of a beacon light according to our new design;

FIG. 2 is a top plan view thereof; and,

FIG. 3 is a front elevation view thereof, with the rear elevation, left side elevation, and right side elevations being identical thereto.

1 Claim, 3 Drawing Sheets

FIG. 1

FIG. 2

FIG. 3
